DESIGN FOR A CYLINDER COMPRESSION GAUGE

George M. Graham, Detroit, Mich., assignor to
Hinckley-Myers Company, Jackson, Mich., a
corporation of Michigan

Application July 3, 1940, Serial No. 93,414

Term of patent 7 years

To all whom it may concern:

Be it known that I, George M. Graham, a citizen of the United States, residing at Detroit, in the county of Wayne and State of Michigan, have invented a new, original, and ornamental Design for a Cylinder Compression Gauge, of which the following is a specification, reference being had to the accompanying drawing, forming part thereof.

In the drawing:

Figure 1 is a view in elevation of a cylinder

compression gauge showing my new design, and
Fig. 2 is a view in cross-section taken on line
2—2 of Fig. 1.

The dominant features of my design are embodied in the portion shown in full lines in the drawing.

I claim:

The ornamental design for a cylinder compression gauge, as shown and described.

GEORGE M. GRAHAM.
